(57) **CLAIM**

The ornamental design for a cone and popsicle protector set, as shown and described.

DESCRIPTION

FIG. 1 is a top plan view of the cone and popsicle protector set, showing my new design;

FIG. 2 is a bottom plan view thereof;

FIG. 3 is a right side elevational view thereof;

FIG. 4 is a front elevational view thereof; and,

FIG. 5 is an isometric view thereof.

The broken lines are included for the purpose of illustrating environmental structure and form no part of the claimed design.
